UNITED STATES PATENT OFFICE.

JOSEPH S. DUNCAN, OF CHICAGO, ILLINOIS, ASSIGNOR TO ADDRESSOGRAPH COMPANY,
OF CHICAGO, ILLINOIS, A CORPORATION OF ILLINOIS.

PRINTING DEVICE.

1,026,252.

Specification of Letters Patent.

Patented May 14, 1912.

Application filed October 24, 1910. Serial No. 588,585.

To all whom it may concern:

Be it known that I, JOSEPH S. DUNCAN, a citizen of the United States, residing at Chicago, in the county of Cook and State of Illinois, have invented new and useful Improvements in Printing Devices, of which the following is a specification.

This invention relates to that class of printing devices referred to in my application filed concurrently herewith October 24, 1910, Serial No. 588,584, and comprising a frame carrying a printing form and adapted to be stored in accordance with a card index system and run through an address-
ing or other printing machine to take an impression therefrom. These devices are used principally for printing addresses and are generally employed by those who send out many bills, circulars or other printed matter regularly to the same customers, such as gas companies, electric light companies, telephone companies, and publishers, as well as bankers, brokers, insurance agents, manufacturers and retailers.

The object of the invention is to reduce the expense of maintaining a system of printing devices of this general character by providing for the renewal of so much only of the printing device as is necessary when changes occur in the address. And a further object of the invention is to provide a sectional printing plate for a printing device of this character with means for securing the sections in the frame so that any section may be renewed without requiring the renewal of the entire plate or form.

In my other application above referred to I have generically claimed and shown one specific form of printing device adapted to attain the objects herein sought but the broad invention may be embodied in another specific form as shown in the accompanying drawings, in which—

Figure 1 is a front view of the printing device. Fig. 2 is a front view of the frame with the card and printing plate sections removed. Figs. 3, 4 and 5 are detail plan views of the printing plate sections.

The general construction and arrangement of parts corresponds closely to that described in my concurrent application, October 24, 1910, Serial No. 588,584, the frame 6 being of any suitable construction and provided with means for detachably securing the card 7 and the sections 8, 9 and 10

of the printing plate thereon. In the form shown the card bearing the inscription produced by the printing plate is held in place by the bead 11, the lips 12 and the end stop 13; the section 10 is detachably held in place on the frame by the locking device 14, the lip 15 and the bead 16; the section 9 is detachably held in place on the frame by the bead 16, the lip 17, the lip 18 and by the section 8 which is itself detachably held in place on the frame by the sections 10 and 9, the projection 19 on the section 9, the lips 20, and the projection 21 on the locking device 22 which engages the recess 23 and by the projection 24 on the frame. The lip 17 is arranged to overlap and engage the sections 8 and 9 at their adjacent right-hand corners and the section 10 is preferably cut out at 17' to accommodate the lip 17 and so that the sections 8 and 9 may engage the adjacent side edge of the section 10. In this embodiment of the invention the section 10 is as wide as the combined width of the sections 8 and 9 and occupies a position at the right of said sections and coöperates with the lip 17 in forming a stop against endwise movement of the sections 8 and 9 in one direction. The section 8 is of less length than the corresponding section in the form disclosed in my concurrent application but for many purposes this construction will be sufficient. The section 10 may be inserted in and removed from the frame without regard to the other sections but the section 9 can only be inserted or removed when the section 8 is not in place. The section 8 may be removed by disengaging the locking projection 21 from the notch 23 to permit said section to be slid out of the frame lengthwise, to the left, and then the section 9 can be removed by sliding it upward until it is disengaged from the lip 18. The section 8 bears the form for printing the name, the section 9 the form for printing the address, and the section 10 the form for printing whatever information is desired. By reason of the fact that the section 10 is of considerable area it is therefore adapted to bear a form for printing considerable information, and this is effected without increasing the size of the frame or the superficial area of the printing plate as a whole.

I use the term "printing plate" herein

broadly to include not only the plate with characters stamped therein as shown, but any kind of printing form suitable for the work, such as a form of separate type or 5 logotype set up in suitable holders adapted to be secured in place on the frame in the manner described. The card is intended to receive an impression from the printing form and any other desired information for 10 reference.

What I claim and desire to secure by Letters Patent is:

1. A printing device comprising a frame provided with printing plate retaining 15 means struck up therefrom, and a printing plate consisting of a plurality of detachable sections, certain of the sections extending lengthwise of the frame in edge engagement with one another, and one of the 20 other printing plate sections being disposed with one of its edges in engagement with corresponding end edges of the first-mentioned printing plate sections, and a retaining lip struck up from the plate and 25 overlapping the ends of said first-mentioned printing plate sections and located between the latter and the second mentioned printing plate section.
2. A printing device comprising a frame, 30 means for retaining a printing plate flat on the frame, and a printing plate consisting of a plurality of detachable sections adapted to be engaged with said retaining

means, two of said sections being arranged longitudinally of the frame with their long 35 edges in engagement with each other and another section being disposed transversely of the frame with its long edge in engagement with the ends of the other sections.

3. A printing device comprising a frame 40 provided with means for retaining a printing plate in position on the frame, and a printing plate consisting of a plurality of detachable sections adapted to be slidably engaged with said retaining means, two of 45 said sections being arranged side by side in mutual edge engagement and another section of a length approximately equal to the aggregate width of the first mentioned sections being disposed with its long edge 50 in engagement with corresponding ends of the other sections.

4. A printing device comprising a frame, a sectional printing plate, two of said sections being arranged side by side with their 55 ends contiguous to a third section, and means for securing said sections on the frame comprising a lip on the frame arranged to engage the adjacent corners of the first two sections, the third section being cut away to accommodate said lip.

JOSEPH S. DUNCAN.
